UNITED STATES PATENT OFFICE.

FREDERICK W. RUBIN, OF INDIANAPOLIS, INDIANA.

SEALING MEANS FOR DOORS, WINDOWS, AND THE LIKE.

1,311,775.

Specification of Letters Patent. Patented July 29, 1919.

Application filed March 11, 1918. Serial No. 221,875.

To all whom it may concern:

Be it known that I, FREDERICK W. RUBIN, a citizen of the United States, and a resident of Indianapolis, county of Marion, and 5 State of Indiana, have invented a certain new and useful Sealing Means for Doors, Windows, and the like; and I do hereby declare that the following is a full, clear, and exact description thereof, reference being 10 had to the accompanying drawings, in which like letters refer to like parts.

This invention relates to adjustable sealing means for doors, windows and the like, and is particularly designed for use with 15 the doors of drying kilns, or in places where the heat within the structure is sufficiently intense to warp the door of the structure. The prime feature of the invention is the provision of strips, preferably of metal, 20 which may be placed end to end around the edges of the door frame.

A further feature of the invention is the provision of pliable sections of fabric and 25 means for attaching the same along one edge of the metal strips so that the fabric will press against the face of the door and prevent air from entering the structure around the edges of the door.

A further feature of the invention is the 30 provision of means for adjusting said strips so as to positively force the fabric against the door regardless of how much out-of-true the door may be.

A further feature of the invention is the 35 provision of means for holding all of the metallic strips in contact with each other end to end.

Other objections and advantages will be hereinafter more fully set forth and pointed 40 out in the accompanying specification.

In the accompanying drawings which are made a part of this application, Figure 1 is a perspective view of a door casing and door such as is commonly used with drying kilns 45 showing the improved sealing means applied thereto; Fig. 2 is a top plan view of two of the sections of the sealing device and Fig. 3 is an edge elevation thereof.

Referring to the drawings in which similar reference numerals designate corresponding 50 parts throughout the several views, 1 indicates the door casing which may be of the usual or any preferred construction, and 2 indicates the door which is preferably 55 mounted upon rollers and slides lengthwise of the door casing when being opened or

closed, as is the case with structures of this class.

In drying kilns, especially with that class employed in drying lumber the door is of 60 sufficient extent to cover one entire end of the drying chamber, and owing to the fact that a high temperature is maintained within the kiln the door frequently becomes warped and so thrown out of alignment, air 65 may freely enter the kiln around the edges of the door and thus detract from the efficiency of the kiln. To over-come this objectionable feature, strips 3, preferably of metal are placed end to end around the edges 70 of the door casing adjacent which the door moves, said strips being held in engagement with the casing by means of bolts 4, which project through elongated slots 5, in the strips 3 and into the adjacent bars of the 75 door casing.

By providing the slots 5, the strips 3 may be moved bodily toward the surface of the door as shown in Fig. 1, to compensate for the warped condition of the door, and in 80 order to prevent air from passing between the ends of the strips and also to hold said strips in engagement with each other, one end of each strip is provided with a curved recess 6 into which takes a curved projection 85 7 on the adjoining end of the next succeeding strip, the ends of the strips on opposite sides of the curved portions being inclined 90 away from each other so that when two or more of the strips are moved inwardly and out of direct alignment with the remainder of the strips, the ends of the strips will not bind against each other.

The front edge of the strip 3 is provided with an offset 8 for the reception of binding sections or strips 9 preferably of fabric, such as canvas, said sections being formed by folding several strips of the canvas together and then clamping the same into the offset by means of plates 10 and rivets 11, 100 a part of the binding sections or strips projecting beyond the metallic strips 3 so that when it is forced against the face of the door it will yield and at the same time adhere closely to the surface of the door, thus 105 completely excluding air from the kiln and to prevent air from entering between the ends of the fabric where the ends of the metallic strips come together, insert sections 12 of the same material from which the 110 binding sections are made are introduced between the folds of the binding sections

and project from the binding section of one strip into the binding section of the adjacent strip, thus forming a continuous strip of binding material.

5 In applying the strips to use, the strips 3 are arranged around the frame 1 adjacent to the edge of the frame over which the door extends after which the door 2 is closed and the strip 3 then adjusted toward the door until the binding materials at the edges of the strips are engaged with the surface of the door at all points around the frame. The bolts 4 are then turned down and the strips 3 securely locked in their adjusted position.

10 It will be noted that the binding sections 9 extend a distance beyond the strips 3 so that the door will readily move to open or closed position although parts thereof will be nearer the edges of the strips than others, the fabric strips yielding sufficiently to permit the movement of the door without binding.

15 In this manner, the air is entirely ex-

cluded from the structure around the door frame, and should the door become warped in a new place or additionally warped, the strips 3 are to be readjusted to compensate for the curvature in the door.

20 The invention claimed is:

In a sealing means for closures, the combination with a casing, and a closure therefor, of a plurality of strips placed end to end and lying flat upon the casing, whereby heavy loads may be moved thereover without affecting said strips, one end of each strip having a curved recess and a projection on the opposite end of each strip adapted to interlock with the recess of the abutting strip for holding said ends in relation 25 with each other, means to adjustably secure the strips to the casing and maintain them in their adjusted position constantly, and flexible means carried by the strips for engagement with the face of the closure.

30 35 40 45 In witness whereof, I have hereunto affixed my signature.

FREDERICK W. RUBIN.
